VALVE LIFTING APPARATUS

Filed April 4, 1925

Patented Jan. 25, 1927.

UNITED STATES PATENT OFFICE.

HARRY C. HUGHES, OF CINCINNATI, OHIO.

VALVE-LIFTING APPARATUS.

Application filed April 4, 1925. Serial No. 20,840.

My invention relates to apparatus for the lifting and removal of valves for grinding the same or valve renewal in automotive engines.

5 The problem of valve lifting and removal is a serious one in automobile practice, because of the confined space in which the operator can work, and the heavy tension of the springs, and the presence of the valve lifters operated by the engine.

10 It is the object of my invention to provide a mechanism and process for removing and replacing of the usual valves found in automotive engines at the present day, same particularly designed to facilitate the elevation of the bottom retaining pan so that the valve key is available and the stem can be lifted clear out of the casing that confines it, and as readily inserted again.

15 The operator is provided with a few simple implements which are easy to employ, and among other things, I provide a threadder for passing through the valve guide, which threadder will hold and guide the 20 spring, and retain the lower pan.

25 I accomplish my objects by that certain construction and arrangement of parts to be hereinafter more specifically pointed out and claimed.

30 In the drawings:

Figure 1 is a section showing a valve in place and seated.

35 Figure 2 is a like view showing the valve raised by the lifting pin and with a retaining tool inserted beneath the pan.

Figure 3 is a like view showing the valve head released so as to lower the retaining pin.

40 Figure 4 is a like view showing the valve removed and the threadder holding the spring and pan in place, with the pan supported by the tool.

Figure 5 is a perspective of the tool.

Figure 6 is a perspective of the threadder.

45 Figure 7 is a perspective of a modified threadder.

Referring to the frame parts of the motor in which the valve is located I have selected a simple form of structure in which the 50 valve seat 1 is in a wall 2 of the machine casing, the guide 3 for the valve stem is supported between two webs 4 and 5, and the lifting pin is mounted and guided in a boss 6 of the casing. I have not shown the cam shaft operation of the lifting pins, which is

as customarily practiced in automobile engines.

The valve is shown as having a head 7, a stem 8, and a key 9. This key 9 holds a pan or dish shaped washer 10 in place against the force of a compression spring 11, arranged around the valve stem and abutting at its upper end against the web 5 of the valve stem guide.

45 The lifting pin 12 engages the lower end of the valve stem and in the operation of the engine raises the valve from its seat.

In carrying out my process the first step is to revolve the engine crank shaft, thereby causing the cam shaft to raise a selected 70 valve stem. When the stem is raised so that the valve is unseated, a tool 7^a can be inserted under the head of the valve to give it an additional lift against the spring, and thereupon the retaining tool 13 is employed. 75

This tool is in the form of bar terminating in a U-shaped piece of sufficient width, which is inserted under the pan on the valve stem resting against the base of the boss 6, or resting at any other convenient point 80. The U-shaped end of the tool is open toward the operator, and is of sufficient diameter to engage the pan without engaging the valve stem or key.

85 The lifter which has propped up the valve head, is removed when the tool has been inserted, thereby permitting the valve stem to drop by gravity, and thereby exposing the key. The valve is turned around until the key is properly presented to the operator, who then reaches into the open space left by the tool, and pulls out the key.

90 The valve is then lifted clear out of the guide spring, and pan. Now the small end of the threadder is pushed up through the 95 pan, spring and valve guide occupying the normal position of the valve stem, Figure 4. The threadder is lowered back through valve guide and removed from engine together with spring and pan. Thereupon 100 the grinding can proceed without interference of the spring.

When the valve is to be replaced, the threadder is also used. It is formed of a fairly stiff wire 14, having a knob 15 secured 105 thereto which is of larger diameter than the valve stem. The operator pushes the end 16 of the wire up through the pan and spring, and through the valve stem guide, so that he can grasp the end 16 from above. A loop 110

at the end 16 will be convenient for handling.

The operator then pulls up on the threader to compress the spring sufficiently to permit 5 the tool 13 to be inserted under the pan again, and pulls the threader back out of the way. He then drops the valve into place with its end coming below the pan within the open portion of the U-shaped tool piece, 10 whereupon he can insert the key, and remove the tool.

The simplicity of this operation will at once recommend itself to anyone who has attempted to remove and grind the valves 15 of an automobile engine.

If the threader is of the form of Figure 7, it can be dropped through the parts from above. The cable 30 of this structure has a ring 31 of less size than the valve stem. 20 When the ring 31 is dropped down through the parts, the pin 32 will be set into the ring so as to prevent the pan from slipping over the ring.

I am aware that it is old to block up the 25 pan of a valve with a piece of metal, so as to get at the key, but my tool is a device which can be readily inserted and removed, and prevents the necessity of fumbling around with a block which may fall out of 30 place, and in fact frequently does do so.

Having thus described my invention, what

I claim as new and desire to secure by Letters Patent, is:—

1. A process of removing and replacing valves from internal combustion engines 35 which consists in first raising the valve rod to compress the spring, then holding up the pan and spring on the valve rod and permitting the stem to drop in a manner that will expose the key, then pulling out the key, and 40 removing the valve, then replacing the valve by a stringer running through the spring and pan and preventing the pan from coming off the stringer, passing the stringer through the valve guide, and pulling it up 45 to compress the spring, and finally reversing the operations now described.

2. A method of replacing valves in internal combustion engines which consists in passing a stringer through the pan and 50 spring, and preventing the stringer from pulling through the pan, passing the stringer through the valve stem guide, and pulling it up to compress the spring, blocking up the pan to hold it in elevated position, removing the stringer, replacing the valve stem to bring the key opening therein below the pan, inserting the key and removing the blocking device, substantially as described. 55

HARRY C. HUGHES.
